UNITED STATES PATENT OFFICE.

RANSOM Y. BOVEE, OF CHICAGO, ILLINOIS.

FOLDING COMBINATION TOILET ARTICLE.

1,258,179.

Specification of Letters Patent. Patented Mar. 5, 1918.

Application filed September 11, 1915. Serial No. 50,161.

To all whom it may concern:

Be it known that I, RANSOM Y. BOVEE, a citizen of the United States, residing at Chicago, in the county of Cook and State 5 of Illinois, have invented certain new and useful Improvements in Folding Combination Toilet Articles, of which the following is a specification.

This invention relates to improvements 10 in folding combination toilet articles, and one of the objects of the invention is to provide an improved, simple, durable and inexpensive device of this character, which will be light in construction and which may 15 be readily unfolded for use and when folded will be compact.

To the attainment of these ends and the accomplishment of other new and useful objects, as will appear, the invention consists 20 in the features of novelty in substantially the construction, combination and arrangement of the several parts, hereinafter more fully described and claimed and shown in the accompanying drawing, illustrating 25 the invention and in which:

Figure 1 is a side elevation of an improved device of this character, constructed in accordance with the principles of this invention and showing the parts unfolded.

30 Fig. 2 is a right hand end elevation of the parts shown in Fig. 1.

Fig. 3 is an elevation showing the device folded.

Fig. 4 is an enlarged detail view of the 35 connecting hinge or joint between the elements.

Fig. 5 is a bottom end elevation of the parts shown in Fig. 3.

The casing is constructed of a single piece 40 of sheet material bent into shape to form the side walls 10, 11 and end wall 12, and the edges of the side walls 10 and 11 are deflected laterally as at 13, and 14 toward each other, and the extremities of these deflected portions are then bent to form the spaced substantially parallel portions 15, 16 to constitute spring members between which members or portions 15, 16 a member 17 projects, and this member is pivotally connected 45 to the portions 15 by means of a suitable pivot pin 18.

The portions 15, 16 are provided with transverse recesses 19 which open inwardly toward the space between the portions 15, 16 and the member 17 is provided with a 55 rib 20, which is adapted to enter the recess 19 to hold the member 17 in its folded or unfolded positions. Supported by the member 17 are comb teeth 21 and a brush 22 may also be supported by the member, the comb 60 and brush being adapted to be folded into the casing, as shown more clearly in Fig. 4.

The casing may be of any desired size and configuration to form a housing for the elements 21, 22 and in order to move the member 17 about its pivot, there is provided a projection 23 connected with the member 17 which acts as a finger hold.

In order to properly position the comb or the brush with respect to the casing in 70 order that they may be used, and to limit the movement of the member 17 about its pivot in one direction, there is provided a stop 24 which is formed from a portion of one of the portions 15, 16 and extends transversely of the space between the portions 15, 16 in a position that a shoulder 25 on the member 17 will abut thereagainst at the same time that the rib 20 enters the recess 19.

The portions 15, 16 being elastic or 80 springy, will hold the brush or comb in position and will yield to permit the member 17 to be moved about its pivot to fold or unfold the article.

Pivotedly connected with one of the side 85 walls, preferably the wall 11, is a toilet implement 26, adapted to be moved about the pivot 30 into and out of the casing.

A button hook 31 is also pivotally connected as at 32 to the side wall 10 of the 90 casing so as to fold into and out of the casing, and the side wall 10 may be notched or recessed as at 32 to assist in unfolding the implement. A similar recess may be provided on the other side of the casing to 95 assist in manipulating the implement 27. The end wall 12 of the casing at the top thereof and adjacent the side walls 11, 12 is notched or recessed as at 33, 34 and these recesses are adapted to respectively receive 100 the implements 27, 31 when the latter are unfolded, and renders it possible to position

these implements properly when desired for use.

A mirror 35 may be secured to the outer face of one of the side members 10, 11 by cutting out portions of said member to form clips adapted to be bent over the edges of the mirror as at 35^a, and the projection 23 may be provided with an aperture or opening 36 for the reception of a chain or the like.

With this improved construction it will be manifest that a very compact structure is provided and that several implements, necessary for toilet purposes, have been combined into one simple structure, of such a size that the implements may be unfolded when desired for use and folded within the casing when the device is not in use.

Obviously the casing may be constructed of any suitable sheet material.

What is claimed as new is:

1. A foldable toilet article comprising a casing embodying spaced members connected at one edge, the opposite edges of the members being deflected toward each other and then laterally with respect to the deflected portions to form spaced substantially parallel spring portions, a member having a portion projecting between said spring portions, a fastening device passing through the last recited member and engaging the said spring portions to form a pivot for the former, whereby the member may be folded into and out of the casing, and inter-engaging means between the last said member and said spring portions adjacent the pivot of the folding member for yieldingly holding the member in folded and unfolded positions, a portion of one of the said spring portions being deflected laterally in a direction across the space between the said portions to form a stop to limit the movement of the pivoted member about its pivot in one direction.

45 2. A foldable toilet article embodying a casing constructed from a single piece of sheet material bent to form a casing having spaced side walls and an end wall, the edges of the said side walls opposite to the end wall being deflected toward and terminating short of each other and then bent laterally to form spaced substantially parallel spring portions, a member projecting between said spring portions and connected with the casing for folding and unfolding pivotal movement with respect thereto, cooperating means on the member and one of the said spring portions adjacent the pivot of the folding member for holding the member in its folded and unfolded positions, and a stop projecting transversely of the space between the said spring portions to form an abutment for limiting the pivotal movement of the member in one direction.

3. A foldable toilet article, embodying a casing constructed from a single piece of sheet material bent to form a casing having spaced side walls and an end wall, the edges of the said side walls opposite to the end wall being deflected toward and terminating short of each other and then bent laterally to form spaced substantially parallel spring portions, a member projecting between said spring portions and connected with the casing for folding and unfolding pivotal movement with respect thereto, said member and one of the said spring portions being provided one with a projection and the other with a groove for receiving the projection, both arranged adjacent the pivot of the member for holding the member in its folded and unfolded positions, a stop projecting transversely of the space between the said spring portion to form an abutment for limiting the pivotal movement of the member in one direction, and a finger hold projecting from the member and by means of which the member may be moved about its pivot.

4. A foldable toilet article embodying a casing shaped to form spaced side walls and an end wall, and elements pivotally connected with the casing one adjacent each side wall and foldable into and out of the casing, the end wall adjacent each of the side walls being shaped to form spaced recesses, each having an elastic wall, said recesses adapted to receive and frictionally hold each of the said elements in unfolded positions.

5. A foldable toilet article embodying a casing formed of a single piece of sheet material shaped to form spaced side walls and an end wall, the edges of the side walls opposite the end wall being shaped to form spaced spring portions, a member projecting between said portions and pivotally connected thereto to fold into and out of the casing, said member and spring portions being provided, adjacent the pivot of the member, one with a projection and the other with a recess for yieldingly holding the member unfolded, and a finger hold connected with the said member for moving the member about its pivot.

6. A foldable toilet article embodying a casing formed of a single piece of sheet material shaped to form spaced side walls and an end wall, the edges of the side walls opposite the end wall being shaped to form spaced spring portions, a member projecting between said spring portions and pivotally connected thereto to fold into and out of the casing, said member and said portions being provided, adjacent the pivot of the member, one with a projection and the other with a recess to receive the projection for yieldingly holding the member in adjusted position, a portion of one of the spring portions

being deflected laterally in a direction across the space between the said spring portions, and a shoulder on the said member adapted to engage said deflected portion to form a stop for limiting the pivotal movement of the said member in one direction.

In testimony whereof I have signed my

name to this specification, in the presence of two subscribing witnesses, on this 9th day of September, A. D. 1915.

RANSOM Y. BOVEE.
